DESIGN FOR A COMBINATION DESK PAD AND VISIBLE RECORD FILE

Benjamin Lapper, Bronx, N. Y., assignor to
National Pad & Tablet Corp., New York, N. Y.

Application October 22, 1940, Serial No. 96,001

Term of patent 14 years

To all whom it may concern:

Be it known that I, Benjamin Lapper, a citizen of the United States of America, residing at 21-26 Vyse Avenue, Bronx County, New York State, have invented a new, original, and ornamental Design for a Combination Desk Pad and Visible Record File, of which the following is a specification, reference being had to the accompanying drawing, forming a part thereof.

Figure 1 is a perspective view of a combination desk pad and visible record file, with cover open, showing my new design.

Figure 2 is a perspective view of a combination desk pad and visible record file, with cover closed, showing my new design.

Figure 3 is a section taken on the line 3—3 in Figure 1.

Figure 4 is a side view of a combination desk pad and visible record file, with cover closed, as shown in Figure 2.

I claim:

The ornamental design for a combination desk pad and visible record file, as shown.

BENJAMIN LAPPER.
